[57] **CLAIM**

The ornamental design for a gasoline pump nozzle trigger holder, as shown and described.

DESCRIPTION

FIG. 1 is a left side, top and front perspective view of a gasoline pump nozzle trigger holder showing my new design;

FIG. 2 is a right side elevational view thereof, the side opposite being a mirror image;

FIG. 3 is a front elevational view thereof; and

FIG. 4 is a top plan view thereof.

FIG. 1

FIG. 2

FIG. 3

FIG. 4
